(57) **CLAIM**

The ornamental design for seat for an ambulatory device, as shown and described.

DESCRIPTION

FIG. 1 is a perspective view of a seat showing the new design;

FIG. 2 is a left side view of the seat of FIG. 1;

FIG. 3 is a back view of seat of FIG. 1;

FIG. 4 is a right side view of the seat of FIG. 1;

FIG. 5 is a front view of the seat of FIG. 1;

FIG. 6 is a top view of the seat of FIG. 1;

FIG. 7 is a bottom view of the seat of FIG. 1;

FIG. 8 is a perspective view of the seat of FIG. 1;

FIG. 9 is a perspective view of a second embodiment of the seat of the new design;

FIG. 10 is a left side view of the seat of FIG. 9;

FIG. 11 is a front view of seat of FIG. 9;

FIG. 12 is a right side view of the seat of FIG. 9;

FIG. 13 is a back view of the seat of FIG. 9;

FIG. 14 is a top view of the seat of FIG. 9;

FIG. 15 is a bottom view of the seat of FIG. 9;

FIG. 16 is a perspective view of the seat of FIG. 9;

FIG. 17 is a perspective view of a third embodiment of the seat of the new design;

FIG. 18 is a left side view of the seat of FIG. 17;

FIG. 19 is a front view of seat of FIG. 17;

FIG. 20 is a right side view of the seat of FIG. 17;

FIG. 21 is a back view of the seat of FIG. 17;

FIG. 22 is a top view of the seat of FIG. 17;

FIG. 23 is a bottom view of the seat of FIG. 17; and,

FIG. 24 is a perspective view of the seat of FIG. 17.
